TICKET ENCODER FOR DATA PROCESSING

Wayne L. Aderman, Zumbro Falls, Minn., assignor to
International Business Machines Corporation, Armonk,
N.Y.

Filed Mar. 13, 1974, Ser. No. 450,645

Term of patent 14 years

Int. Cl. D14—02

U.S. Cl. D26—5 C

FIG. 1

FIG. 2

FIG. 3

FIG. 1 is a right front perspective view of a ticket encoder showing my new design;

FIG. 2 is a left front perspective view of said ticket encoder; and

FIG. 3 is a rear elevation, taken 30° above the horizontal, of said ticket encoder.

I claim:

The ornamental design for a ticket encoder for data processing, as shown.
